BALLOT

Charles W. Foster, Kansas City, Mo.

Application July 18, 1938, Serial No. 219,710

6 Claims. (Cl. 283—5)

My invention relates to improvements in ballots. It relates particularly to ballots that may be prepared by the voters and mailed by them to the proper officials.

Some of the objects of my invention are to provide a novel ballot that will keep in secrecy, excepting to the proper officials, the voter's name and how he has voted; which has novel means by which the voter designates the candidates for whom he votes; which has novel means for the identification to the proper officials of the voter who has cast the ballot; which has novel means for guarding against tampering with or changing the ballot cast; which is adapted for quick counting mechanically by usual vote counting machines; which of itself provides the means by which the voter may apply his finger prints to the ballot for identification purposes; and which may be easily and quickly prepared by the voter for mailing or casting in a receptacle therefor.

The novel features of my invention are herein-after fully described and claimed.

In the accompanying drawing, which illustrates the preferred embodiment of my invention,

Fig. 1 is a plan view of my improved ballot before it has been operated upon by the voter who is to cast it, the guard flap being shown in the open position.

Fig. 2 is a section on the line 2—2 of Fig. 1.

Fig. 3 is a view similar to Fig. 1, the finger moistening pad having been removed from the ballot, as have been the tabs opposite the names of candidates voted for; the voter's finger prints being shown applied to the ballot; the guard flap being shown in solid lines in the open position, and shown in dotted lines in the closed or tab covering position.

Fig. 4 is a section on the plane of the line 4—4 of Fig. 3, showing the ballot in proper form for casting or mailing.

Similar characters of reference designate similar parts in the different views.

1 designates a base sheet of suitable material, as cardboard or heavy paper, and which has dimensions suitable for accommodating the names of the candidates to be voted for; the information that it is desired to impart; and the finger prints of the voter.

50 In a column on the front of the base sheet 1 are printed the names of the candidates spaced apart one name above the other, as "A. Jones," "B. Long," "C. Gray," "D. Cook," "E. Nash," and "F. Paine."

55 The base sheet 1 has extending through it holes

2, longitudinally aligned and disposed at the left of and respectively opposite the names of the candidates.

Mounted upon the base sheet 1 and covering the holes 2 is a second sheet 3 of paper or other suitable material, which in its right edge portion is provided with a longitudinal row of detachable tabs 4, which project from the right edge of the sheet 3, so as to be easily gripped for detachment purposes. The tabs 4 are disposed respectively over and cover the holes 2, the latter being opened upon the detachment of the tabs. The upper, lower and left edges of the tabs 4 are demarcated from the rest of the sheet 3 by lines of perforations 5, to enable the easy detachment of the tabs, the under sides of which are not fastened to the base sheet 1, excepting as being a part of the sheet 3.

To vote for a candidate, the voter detaches the tab 4 opposite to the name of the candidate. 20 Thus, as shown in Fig. 3, the tabs 4 opposite the names respectively of "Long," "Gray," "Cook," and "Paine" have been detached, showing that the candidates having these names have been voted for. The tabs 4 opposite the names "Jones" and "Nash" not having been removed, the candidates having these two names have not been voted for.

To prevent any felonious tampering with the tabs 4, after the voter has cast his ballot, the sheet 3 is provided in its left portion with a flap 6, which is connected with that portion of the sheet 3 mounted on the base sheet 1, by a weakened portion indicated by the dotted lines 7 adjacent to and parallel with the left edge of the base sheet 1. This weakening along the lines 7 may be effected by so creasing the sheet 3 as to enable the flap 6 to fold flatly over and upon the front of the base sheet 1, as shown in dotted lines in Fig. 3, and in solid lines in Fig. 4.

To seal the flap 6 in this closed or covering position, its upper and lower and left edge portions, on the side which is to be next to the sheet 1, has a coating 8 of muscilage, which, on being moistened, and the flap pressed at its edges 45 against the sheet 3 and the base sheet 1, will securely seal the flap to the two sheets, and will prevent felonious access to the space covered by the flap when in said closed position.

In order that the automatic machines which are used to count votes, in the usual manner, 50 the flap 6 is provided therethrough with a longitudinal row of holes 9, which, when the flap 6 is sealed in the closed position, as shown in Fig. 4, will align with the row of holes 2 and will 55

respectively register therewith, thus enabling the vote counting machine to properly operate upon the ballot when it has been cast. The tabs which have not been detached, will close the holes which they overlie, and thus prevent the vote counting machine registering votes for the names opposite such closed holes.

The flap 6 may be opaque or transparent, as desired. If transparent, it may be noted at a glance without detachment of the flap 6, what candidates on the ballot have been voted for. The term "transparent" as herein used, means sufficiently clear to enable the noting of the presence or absence of tabs by looking through the flap.

For identification purposes, a space 10 is provided on the front of the base sheet 1, above the candidates names, for the inscription thereon of the voter's official voting number, as "No. 67,058."

For finger print identification of the voter, there are provided on the front of the base sheet 1 at the right of the candidates names, two columns of five spaces, 11, each. These spaces 11 are surface treated with any one of the usual finger printing material, as finger printing ink, that is adapted to be used in connection and to cooperate with another commonly used finger printing liquid, with which a pad 12 is moistened. The pad 12 is mounted upon the front of the base sheet 1 at the right edge portion thereof, and next adjacent to the right column of finger print spaces 11.

The base sheet 1 between the portion carrying the pad 12 and the adjacent spaces 11 is weakened by a longitudinal line of perforations 13, Figs. 1 and 2, whereby the pad and the portion of the base sheet 1 carrying the pad, can be detached from the ballot after the voter has applied his finger prints thereto.

The column of spaces 11 at the left are intended to receive the finger prints of the right hand, the lowest space in the column being marked "Thumb," and "R. Hand," and the spaces above being marked "2nd," "3rd," "4th" and "5th," and intended to receive the prints of the fingers of the right hand, as indicated by the marks. The right column of spaces are similarly marked to designate a similar application of the prints of the fingers of the left hand thereto. In Fig. 3, the circles 14 in the spaces 11 respectively represent the finger prints that have been made on said spaces.

In voting the ballot, the voter first detaches the tabs 4 from opposite the names of the candidates for whom he desires to vote. He then moistens the mucilage coating 8 on the flap 6, and folds and seals the flap to the front side of the base sheet 1 and the sheet 3, thus covering the tabs remaining, the holes from over which tabs have been removed, and the names of the candidates.

The holes 9 in the flap 6 will register with the holes 2 from over which the tabs have been removed, so that the votes cast may be machine counted without removing the flap 6.

The voter then moistens the fingers of his hands on the pad 12, and applies them in the manner already described to the chemical treated spaces 11, thereby affixing his finger prints, designated by 14 on Fig. 3, on the ballot. The voter then detaches the pad 12 and its supporting part of the base sheet 1 along the perforations 13. The ballot may then be mailed or cast into a receptacle designed to receive it.

The ballot can be counted by the usual type of vote counting machine, which operates to count the votes through holes in the ballot.

It is preferable to employ the separated finger printing materials on the spaces 11 and the pad 12, as described, as the materials commonly used together in this manner will not separately make indelible marks, and smearing with the fingers will be eliminated. However, if desired, the pad 12 may be moistened with a usual finger printing ink, and this ink employed alone for moistening the fingers to be printed on the ballot. In such case, preliminary treatment of the spaces 11 may be dispensed with.

With either of these two methods employed, the ballot, of itself, provides the means for making the finger prints thereon.

In place of counting the votes with a machine, they, of course, can be counted by noting the perforations which extend clear through the flap and base sheet.

For treating the spaces 11 and for moistening the pad 12, the materials commonly used by the Government operatives and those of police departments may be employed.

For example, the spaces 11 may be treated with tannic acid, the pad moistened with a soluble salt of vanadium, such as sulphate of vanadium.

Other modifications of my invention, within the scope of the appended claims, may be made without departing from the spirit of my invention.

What I claim is:

1. A ballot comprising in combination a base sheet having inscribed thereon the names of candidates, and having holes through said sheet respectively opposite said names, removable tabs on the front of said sheet respectively covering said holes, and a flap attached to said sheet and adapted to be swung to and from a position in which it will cover said tabs and holes and having means for being sealed to said sheet in said closed position to prevent felonious access to the space covered by said flap. 35

2. A ballot comprising in combination a base sheet having inscribed thereon the names of candidates, and having holes through said sheet respectively opposite said names, removable tabs on the front of said sheet respectively covering said holes, and a flap attached to said sheet and adapted to be swung to and from a position in which it will cover said tabs and holes and having means for being sealed to said sheet in said closed position to prevent felonious access to the space covered by said flap, said flap having holes therethrough which, when said flap is in said position, respectively register with said holes in said sheet. 50

3. A ballot comprising in combination a base sheet having inscribed thereon the names of candidates, and holes through said sheet respectively opposite said names, removable tabs on the front of said sheet respectively covering said holes, and a transparent flap attached to said sheet and adapted to be swung to and from a position covering said tabs and holes and having means for being sealed to said sheet in said closed position to prevent felonious access to the space covered by said flap, when in said position. 60

4. A ballot comprising in combination a base sheet having inscribed thereon the names of candidates, and holes through said sheet respectively opposite said names, removable tabs on the front of said sheet respectively covering said holes, and an opaque flap attached to said sheet and adapted 70

to be swung to and from a position covering said tabs and holes and having means for being sealed to said sheet in said position to prevent felonious access to the space covered by said flap, when in 5 said position.

5. A ballot comprising in combination a base sheet having inscribed thereon the names of candidates and holes through said sheet respectively opposite to said names, and a second sheet fastened 10 to the front side of said base sheet and having tabs respectively covering said holes and having weakened attachment to said second sheet to enable their easy detachment therefrom, said second sheet having a flap adapted to be swung 15 to and from a position covering said tabs and holes and having means for being sealed in said position to prevent felonious access to the space covered by said flap, when in said position.

6. A ballot comprising in combination a base sheet having inscribed thereon the names of candidates and holes through said sheet respectively opposite to said names, and a second sheet fastened to the front side of said base sheet and 5 having tabs respectively covering said holes and having weakened attachment to said second sheet to enable their easy detachment therefrom, said second sheet having a flap adapted to be swung to and from a position covering said tabs and holes 10 and having means for being sealed in said position to prevent felonious access to the space covered by said flap when in said position, said flap having holes therethrough which, when said flap is in said position, respectively register with said 15 holes in said base sheet.
